UNITED STATES PATENT OFFICE.

HOWARD L. UNGERER AND DAVID W. HUGHES, OF NEW YORK, N. Y., ASSIGNORS TO ELEVATOR SUPPLIES COMPANY, INC., OF HOBOKEN, NEW JERSEY, A CORPORATION OF NEW JERSEY.

ELEVATOR-CONTROL APPARATUS.

Application filed March 13, 1926. Serial No. 94,409.

This invention relates to control apparatus for elevators and particularly to elevators electrically controlled, whether such control is centered in the car or at the various landings along the hatchway in which the car travels.

An object of the invention is to provide safety interlocking means whereby (except in case of emergency, such as fire) the car 10 cannot be started away from any landing unless and until all hatchway doors are closed and mechanically locked in closed position; and furthermore to render it impossible to reopen, or even to unlock, any hatchway door until the car reaches the landing where such door is located and stops.

A further object of the invention is to provide means for locking the hatchway door in open position while the car is at rest 20 at any landing; thereby removing the obligation from the operator, (or, in the case of passenger controlled elevators of the so-called "push-button type", from the passenger using the elevator), of holding the same open during the period it takes for the passengers to get in or out.

This arrangement is particularly appropriate where the doors are of the self-closing type. When our novel apparatus is applied 30 to doors of this type, the release of the open-position lock on the corridor door allows the door to close, and lock in the closed position; after which the car will be free to move to another landing.

Our invention is equally applicable in the absence of power means for closing the doors, with the exception that in such a case it will be necessary for the operator of the car to close the door after removing the lock. 40 In the preferred embodiment, however, the doors are intended to be self-closing, so that removal of the open-position lock, closure of the doors, locking the doors in closed position and completion of the safety interlock 45 circuit will be accomplished by a single initial act of the operator; in addition to which, if desired, the control of the car may also be centered in the same mechanism, so that movement away from the landing will follow automatically upon the completion of the foregoing operations.

Other objects and advantages to be ob-

tained by the use of our novel apparatus will be apparent as the description progresses, reference being had to the accompanying 55 drawings, wherein:

Fig. 1 shows an elevator and hatchway with our invention applied thereto.

Fig. 2 shows the interlocking mechanism as it appears when the elevator is opposite a 60 landing with the corridor door in the open position.

Fig. 3 shows the same with the corridor door in closed position.

Fig. 4 is a plan view of the parts appearing in Fig. 3.

Figure 5 is a larger view of some of the parts shown in Fig. 1.

Referring to Fig. 1, reference character 1 designates the elevator hatch in which car 2 70 is adapted to travel; a landing along said hatch being indicated at 3, and the corridor door for the landing at 4. Our novel interlocking apparatus, indicated generally by numeral 5 in this figure, is shown mounted 75 in the preferred location, namely, on the landing door sill 6.

In cases where the elevator is equipped with a door similar to door 4, this interlocking apparatus, if desired, may also be placed 80 on the sill of the elevator; but inasmuch as the construction and operation is the same for any door, and involves a mere duplication of parts, we have considered it sufficient for the purposes of this disclosure to illustrate the apparatus at only one door, namely the door 4.

As shown in Fig. 1 the landing door 4 is in closed position, the car 2 being in motion and descending toward landing 3. In this 90 position of the door 4, pawl 7, located on door 4 in the proper position for the purpose, engages ratchet teeth 8 on the sill mechanism 5 holding the door firmly locked in closed position, as will be more clearly 95 apparent as the description progresses.

Near the other end of the sill mechanism is located a projecting member designed and placed so as to be normally clear of the path of elevator 2, but so as to be engaged by a 100 transversely movable member on the elevator when the latter member is projected. The projecting member of the sill mechanism is shown in the preferred embodiment

as a rocker arm, as illustrated at 10 in the drawings, with a roller 11 at the outer end. The transversely movable member on the car is preferably an elongated flat sided shoe, or cam, as it is more commonly termed in the art, this cam being designated by numeral 12.

Obviously the relative arrangement and construction of the cam 12 and the roller 11 can be varied without departing from the scope of my invention, but as shown in the drawings, I prefer to mount the cam 12 so that it will be held in the position shown in Fig. 1 while the car is in operation, in which position it clears roller 11; so that if it is not intended that the car shall stop at landing 3, no engagement between these two parts will occur as the car passes by.

If, however, it is desired to stop the car at landing 3, cam 12 will be caused to project into engagement with roller 11, with the following consequences: The pawl 7 will be released from its engagement with teeth 8, thereby breaking the electric circuit to the car hoisting motor (in a manner to be described) and permitting the door 4 to open to discharge or take on passengers.

Door 4 will be held locked in the open position (by means which will hereinafter be described) until such time as the car operator or user elects to start the car away from landing 3; at which time cam 12 will be retracted again to the position shown in Fig. 1. Retraction of cam 12 will cause the release of the locking apparatus just referred to and will permit the door to close. Closing of the door again restores the electric circuit to the hoisting motor, and the car is free to move away.

A more detailed description of the interlocking mechanism 5 will now be given. At either end of the mechanism, and at the proper points on sill 6, is placed a block as shown at 13 and 14, as shown in Figs. 2 to 4, block 13 being of a solid metallic construction while block 14 is hollow. In fact block 14 is in reality a box standing on edge, the cover being removed in the drawings to show the interior, in which is mounted a circuit making and breaking device comprising in its preferred form an insulated base 16, free to rock to some small extent in its fastenings as illustrated, a pair of thin sheet metal contacts 17, and a roller 18 rotatably mounted in jaws 19, 19 on switch arm 20, these jaws being made of insulating material.

To each of the vertically disposed spring metal contacts 17 (which are adapted to grip roller 18) is secured a conductor, as shown at 21 and 22, these conductors leading to terminal block 23, thru which point the circuit to the elevator controlling motor passes. An inspection of Figs. 2 and 3 will show that this circuit is made when switch

arm 20 is in the position shown in Fig. 3, but broken when the arm is in the position shown in Fig. 2.

Arm 20 is pivoted at 24 to box 14, and, except when restrained as in Fig. 3, normally assumes the position illustrated in Fig. 2 due to the overbalancing weight to the left of the pivot point 24, as indicated at 25.

Integral with arm 20, and upstanding therefrom is a substantially right-angled lug 26, the horizontal or nose portion of which, as indicated at 27 in Figure 3, is adapted to ride on pin 28 projecting from bar 29, an explanation of the purpose of which will hereinafter appear.

Bar 29 is arranged to fit loosely in a groove in the upper portion 31 of the rear wall of box 14, and is loosely held in place preferably by means of two pins 30, 30, extending thru the wall 31. Suitable slots are placed in bar 29 to allow passage of pins 30, 30 therethrough, the slot for the left-hand pin 30 being shown at 32 in Fig. 2. As illustrated these slots extend diagonally along bar 29, thereby allowing upward and outward movement of the bar with respect to box 14, from the position shown in Fig. 3. The means for producing this upward and outward movement will be described shortly.

On the opposite end of sill mechanism 5 is a bar 34 similarly slidable in groove 35 in block 13 by means of two similar pins and slots, the only difference being that in bar 34 the diagonal slots extend upwardly in the reverse direction, as indicated at 36 in Fig. 3.

The preferred means whereby movement of roller 11 (due to engagement of cam 12 therewith) causes the diagonal movements of bars 29 and 34 in opposite directions will now be described, but it is to be understood that other mechanisms may be employed for accomplishing the object. Projecting from arm 10 and loosely threaded thereto is a T-head bolt, as indicated at 36^a in Fig. 4. In the head of this bolt is drilled a hole thru which rod 38 is inserted for sliding movement therein. Very little relative movement between arm 10 and rod 38 can take place, however, because the two are held substantially rigid by means of nuts 39^a, 40^a threaded on rod 38. Consequently movement of one will impart corresponding movement to the other.

At its other end rod 38 passes thru a hole in another guide, (also a T-head bolt in the preferred construction, as shown at 39). This bolt 39 is secured to yoke 40. Yoke 40 serves to retain bar 34, which is pivotally secured thereto by means of bolt 39, which extends through the yoke. By this means movement of arm 10 to the right from the position of Fig. 3 to the position of Fig. 2 will cause corresponding downward and in-

ward movement of bar 34 from the position of Fig. 3 to that of Fig. 2.

Slidably mounted in bearing 42 is a connecting rod 43 which, near its left-end, passes thru a hole in the lug 44 which depends from yoke 40. At the right-hand end rod 43 is supported in a similar manner from yoke 45 which is pivotally secured to bar 29 in the manner indicated.

10 Rod 43 thus forms the connecting link between bars 29 and 34, causing these bars to move in unison upon the actuation of roller 11. Suitable means, such as nuts 46 to 50, are provided for positioning the rod with respect to the two yokes 40 and 45. Nuts 46 to 48 serve the additional purpose of providing the means for adjusting the tension on spring 51, the latter being compressed when roller 11 is thrown by cam 12 to the 15 position of Fig. 2, and also serving to restore the roller to the position of Fig. 3 when the cam is retired.

Spring 52, the tension on which is adjustable by means of nuts 40^b and 53 is provided 20 on rod 38 as a further resistance to the movement of roller 11, but due to its location this latter spring serves to prevent overtravel of the roller 11 rather than to resist the routine operation of the roller. Consequently, 25 in the position shown in Fig. 2, spring 51 only has been materially compressed; but if, for any reason, a greater push were exerted against roller 11, spring 52 would begin to compress, thereby resisting this extraordinary force, since it is obvious from an inspection of Fig. 2 that bar 34, (and hence yoke 40) is positively restrained from any further movement to the right, by reason of the limitation imposed on the movement of 30 the said bar by the length of slots 36 in which the fixed pins previously described are inserted.

The means provided for engagement of the locking mechanism with the door 4 will 40 now be described. At the outer end of each of the bars 29 and 34 is placed a device for limiting the travel of pawl 7, hence the travel of door 4, to which the pawl is connected by means of plate 15. This device also serves 45 to positively direct the pawl 7 in its locking function, and comprises in each case an F-shaped casting consisting of two horizontal members 55 and 56 and the supporting vertical member 57.

50 The upper member 55 has on its under surface a beveled portion 58 which aids in directing the application of pawl 7 against ratchet teeth 8 and nose 27 when the shoulder 59 of pawl 7 comes into engagement therewith as the door reaches its fully closed position. Just prior to this, however, pin 60 secured to pawl 7 near the lower end of the same, strikes the similarly beveled portion 61 on lower member 56; which lower member 65 is so positioned with respect to pin 60

that when bar 29 is in the lower position as shown in Fig. 3 the pin just clears the under surface of the member 56, as shown best in Fig. 3. Consequently, since pin 60 is secured to pawl 7, the member 56 serves to prevent any upward movement of the pawl, thereby insuring that the pawl (hence the door) will remain in this (door closed) position until released by actuation of roller 11 in the manner previously described. Furthermore, since the pawl sits upon the nose 27 of switch 20 in this position, it will be obvious that the circuit therethrough will remain closed until roller 11 is actuated.

Projection of roller 11 to the right, when 80 it is desired to open the door, will cause upward and outward movement of bar 29, and consequently of members 55 and 56, in the manner heretofore explained. This will permit opening movement of door 4, since bar 85 29, then being in the position shown in Fig. 2, will raise pawl 7 above the level of teeth 8, so that the latter will ride along the bar until clear of the same.

On clearing bar 29, pawl 8 will drop to a 90 central disposition with respect to pivot 62 due to the force of gravity, which disposition it will maintain until it strikes bar 34 in its leftward movement. From this point it will ride along the bar and over 95 teeth 63 on block 13 until pin 60 strikes the lower member 64 of the left-hand F-shaped member, which is in every respect similar in construction to the right-hand member just described, and which fulfills a similar 100 function; namely, the locking of pawl 7 against ratchet teeth 63, and consequently, the locking of the door in the full open position.

The door will remain in this locked position until it is desired to close the same, when cam 12 will be retired, permitting 105 spring 51 to return the parts to the position of Fig. 3, in which position the door is free to close and will close and lock in the manner already described.

In practice a plurality of ratchet teeth 8 are provided as shown, as an extra safeguard, but obviously only the inner pair are brought into use for locking purposes in 115 the door closed position. In the door open position, however, the plurality of teeth is an advantage, because they serve to lock the door open even though it did not quite travel to its full open position. But in the door 120 closed position it is necessary that the door travel the full distance, for otherwise no circuit is made through the interlock switch roller 18.

Any of the well-known means for controlling the alternate projection and retraction of cam 12 may be employed, but Fig. 5 shows my preferred construction, the type illustrated in this figure being known in the art as the torque motor control, and being 125 130

described and illustrated in connection with magnetically controlled door operation for elevators in patents to Norton Nos. 1,545,164 and 1,557,309, issued on July 7, 1925, and Oct. 13, 1925, respectively.

As shown in Fig. 5 there is connected to the outer end of bell crank lever 90 (which lever is pivoted centrally to plate 91 attached to the car frame) a chain or cable 92 which is held taut when motor 94 is energized by virtue of its being wound around the shaft of crank arm 93, geared to the shaft of motor 94.

While it is to be understood that our interlocking mechanism may also be operated by a manually controlled cam, nevertheless the magnetic control of the type just referred to is preferable, particularly for use with push-button elevators, which require no operator in constant attendance.

When used with this type of elevator, the operation is as follows:

When it is desired or permissible to move the car away from the landing, the magnetic device 94 is energized, thus withdrawing the cam 12 from engagement with roller 11 and releasing the open-position lock, thereby permitting the door 4 to close, the safety switch arm 20 to make contact, and the car to move away.

As is obvious, the office of the motor 94 which is normally energized while the car is moving, is to hold the cam retracted during such time, and then to free the same for projection by spring 95 or other device when the car is at the selected landing, through interruption of the charging circuit of the motor by any desired means, such as for instance the means commonly employed in the operation of a push-button system of elevator control. Projection of the cam removes the door lock and breaks the safety circuit, allowing the door to open and the intended user of the car to enter and assume control thereof, repeating the operations just described.

Other constructions, arrangements, and adaptations of our novel mechanism may be made by persons skilled in the art without departing from the scope of our invention, as disclosed herein, and as defined in the appended claims.

We claim:

1. In an interlocking mechanism for elevators in combination with a car and a hatch therefor, a door in said hatch, a device in the hatch positioned to restrain movement of said door from the fully open position, means (on the car) for releasing said restraining device and permitting the door to close, a control circuit for the car, a switch in said circuit, and means to close said switch operated by a member movable with said door.

2. In an interlocking mechanism for ele-

vators in combination with a car and a hatch therefor, a door in said hatch, a device in the hatch positioned to restrain movement of said door from the fully open position, means (on the car) for releasing said restraining device and permitting the door to close, a control circuit for the car, a switch in said circuit, and means to close said switch and lock said door in closed position operated by a member movable with said door.

3. In an interlocking mechanism for elevators in combination with a car and a hatch therefor, a door in said hatch, a ratchet device in the hatch, a pawl on the door engaging said ratchet device to lock the door in closed position, a control circuit for the car, a switch in said circuit, and means operated in response to the engagement of said pawl and ratchet device to close said switch.

4. In an interlocking mechanism for elevators in combination with a car and a hatch therefor, a door in said hatch, a control circuit for the car, a switch in said circuit, a ratchet device in the hatch, and a pawl on said door engaging said switch and ratchet device in the closed position of said door.

5. In an interlocking mechanism for elevators in combination with a car and a hatch therefor, a door in said hatch, a control circuit for the car, a switch in said circuit, a ratchet device in the hatch, and a pawl on said door engaging said ratchet device in the open position of the door.

6. In an interlocking mechanism for elevators in combination with a car and a hatch therefor, a door in said hatch, a pair of ratchet devices in the hatch, and a pawl on said door engaging one of said ratchet devices in the open position of said door, and engaging the other of said ratchet devices in the closed position of said door.

7. In an interlocking mechanism for elevators in combination with a car and a hatch therefor, a door in said hatch, a control circuit for the car, a switch in said circuit, a pair of ratchet devices in the hatch, and a pawl on said door engaging one of said ratchet devices and said switch in the closed position of said door.

8. In an elevator control apparatus, in combination with a car and a hatch therefor, a door in said hatch, a means to prevent reverse movement of said door when the latter is in open position, comprising a ratchet mechanism, and magnetically controlled means to release said ratchet mechanism.

9. In an elevator control apparatus, in combination with a car and a hatch therefor, a door in said hatch, a locking means engaging said door when the latter is in the closed position, a control circuit for said car, a switch in said circuit, means for removing said locking means and simultaneously opening said switch, a ratchet mechanism

for locking said door in the open position, and means cooperating with said ratchet mechanism for maintaining said switch in the open position.

5 10. In an elevator control apparatus, in combination with a car and a hatch therefor, a door in said hatch, a locking means engaging said door when the latter is in the closed position, a control circuit for said 10 car, a switch in said circuit, a transversely movable member on the car operable to remove said locking means and open said switch when the car is adjacent said door, a ratchet mechanism for locking said door in 15 the open position, and means to release said ratchet mechanism prior to the closure of said switch.

11. In an elevator control apparatus, in combination with a car and a hatch therefor, a door in said hatch, a pair of ratchet mechanisms for governing the movement of said door, and means for simultaneously operating said ratchet mechanisms.

12. In an elevator control apparatus, in combination with a car and a hatch therefor, a door in said hatch, a pair of ratchet mechanisms for governing the movement of said door, and a transversely movable element on the car for simultaneously operating said ratchet mechanisms.

13. In an elevator control apparatus, in combination with a car and a hatch therefor, a door in said hatch, a control circuit for said car, a switch in said circuit, and a plurality of ratchet mechanisms governing the movement of said door and switch.

14. In an elevator control apparatus, in combination with a car and a hatch therefor, a door in said hatch, a control circuit for said car, a switch in said circuit, a plurality of ratchet mechanisms governing the movement of said door and switch, and a movable element on the car for actuating said ratchet mechanisms.

15. In an interlocking mechanism for elevators, in combination, an elevator and a hatch therefor, a door for ingress to and egress from said elevator, and locking means for said door comprising an element on said door, and mechanism mounted in the hatch and positioned to engage said element to prevent closing movement of the door when the door is in the opened position, said mechanism further operating to prevent opening movement of the door when the latter is in its closed position.

16. In an interlocking mechanism for elevators, in combination, an elevator and a hatch therefor, a door in said hatch and locking means for said door comprising an element movable with said door and co-operating mechanism in the hatch, a part of said mechanism being positioned to engage said element to prevent reverse movement of the door when the door is fully opened,

and another part positioned to engage said element to prevent reverse movement of the door when the latter is fully closed.

17. In an interlocking mechanism for elevators, in combination, an elevator and a hatch therefor, a door in said hatch, locking means for said door comprising an element movable with said door and co-operating mechanism in the hatch, a part of said mechanism being positioned to engage said element to prevent reverse movement of the door when the door is fully opened, another part positioned to engage said element to prevent reverse movement of the door when the latter is fully closed, and means on the elevator for removing said element from its engagement with said mechanism.

18. In an interlocking mechanism for elevators, in combination, an elevator, a door for ingress to and egress from said elevator, means to prevent a closing movement of said door when the latter is in open position, comprising a ratchet mechanism and a pawl for engaging said ratchet mechanism, and means for preventing operation of the elevator while said pawl is in engagement with said ratchet mechanism.

19. As a sub-combination in a locking mechanism for elevator doors, an elevator and a door for entry thereto and exit therefrom, a sill for said door, a pair of locking devices on said sill, and means on said door for engaging one of said locking devices in the open position of said door, and engaging the other of said locking devices in the closed position of said door.

20. As a sub-combination in a locking mechanism for elevator doors, an elevator and a door for entry thereto and exit therefrom, a sill for said door, a pair of ratchet mechanisms on said sill, and a pawl on said door for engaging one of said ratchet mechanisms in the open position of said door, and engaging the other of said ratchet mechanisms in the closed position of said door.

21. As a sub-combination in a locking mechanism for elevator doors, an elevator and a door for entry thereto and exit therefrom, a sill for said door, a pair of ratchet mechanisms on said sill for alternately restraining movement of said door, and means for simultaneously operating said locking devices.

22. As a sub-combination in a locking mechanism for elevator doors, an elevator and a door for entry thereto and exit therefrom, a sill for said door, a pair of locking devices on said sill for alternately restraining movement of said door, and a single operating means for said locking devices.

23. As a sub-combination in a locking mechanism for elevator doors, an elevator and a hatch therefor, a door for entry thereto and exit therefrom, a pair of locking de-

vices in said hatch for alternately restraining movement of said door, and means for placing one of said locking devices in position to prevent opening movement of said door, said means further operating to simultaneously render the other locking device ineffective to prevent closing movement of said door.

24. As a sub-combination in a locking mechanism for elevator doors, an elevator, a door for entry thereto and exit therefrom, a pair of locking devices for alternately restraining movement of said door, comprising a member on said door and a pair of co-operating members movable into the path of said first-named member, and means for moving one of said co-operating members into the path of said first-named member, said means further operating to simultaneously withdraw the other co-operating member from the path of said first-named member.

25. In an elevator control apparatus, in combination, an elevator and a door for entry thereto and exit therefrom, a control circuit for said elevator, a switch in said circuit, means for alternately restraining movement of said door comprising a pair of locking devices, and means for placing one of said locking devices in position to prevent closing movement of said door, said means further operating to simultaneously release said switch and render the other locking device ineffective to prevent opening movement of said door.

26. In an elevator control apparatus, in combination, an elevator and a door for entry thereto and exit therefrom, a control circuit for said elevator, a switch in said circuit, means for alternately restraining movement of said door comprising a pair of locking devices, and means for placing one of said locking devices in position to prevent opening movement of said door, said means further operating to simultaneously close said switch and render the other locking device ineffective to prevent closing movement of said door.

27. In an elevator control apparatus, in combination, an elevator and a door for entry thereto and exit therefrom, a control circuit for said elevator, a switch in said circuit, means for alternately restraining movement of said door comprising a pair of ratchet mechanisms, and means for placing one of said ratchet mechanisms in position to prevent closing movement of said door, said means further operating to simultaneously release said switch and render the other ratchet mechanism ineffective to prevent opening movement of said door.

28. In an elevator control apparatus, in combination, an elevator and a door for entry thereto and exit therefrom, a control circuit for said elevator, a switch in said circuit, means for alternately restraining movement of said door comprising a pair of ratchet mechanisms, and means for placing one of said ratchet mechanisms in position to prevent opening movement of said door, said means further operating to simultaneously close said switch and render the other ratchet mechanism ineffective to prevent closing movement of said door.

29. In an elevator control apparatus, in combination with a car and a hatch therefor, a door in said hatch, locking means for said door comprising an element movable with said door and co-operating mechanism in the hatch, a part of said mechanism being positioned to engage said element to prevent reverse movement of the door when the door is fully opened, said mechanism further operating to engage said element to prevent reverse movement of the door when the latter is fully closed, lock releasing means serving to disengage said element from said hatch mechanism, a control circuit for the elevator, a switch in said circuit, and means for opening said switch simultaneously with the operation of said lock releasing means.

Signed at Hoboken, New Jersey, on the 11th day of March, 1926.

HOWARD L. UNGERER.
DAVID W. HUGHES.
